CLAIM

(57) The ornamental design for an abrasive skin treatment device, as shown and described.

DESCRIPTION

FIG. 1 is a back perspective view of an abrasive skin treatment device in accordance with the present design; FIG. 2 is a front perspective view thereof;

FIG. 3 is a top view thereof;

FIG. 4 is a bottom view thereof;

FIG. 5 is a right side view thereof;

FIG. 6 is a left side view thereof;

FIG. 7 is a back view thereof; and,

FIG. 8 is a front view thereof.

The broken lines are for illustrative purposes only and form no part of the claimed design. The shading represents contour of the claimed design.
